TESTING INSTRUMENT AND REGULATOR

Filed Sept. 16, 1929

Inventor
Penrose E. Chapman

UNITED STATES PATENT OFFICE

PENROSE E. CHAPMAN, OF ST. LOUIS, MISSOURI

TESTING INSTRUMENT AND REGULATOR

Application filed September 16, 1929. Serial No. 392,830.

The object of my invention is to render the armature testing instrument revealed in my Patent No. 1,759,479, issued May 20, 1930, adjustable; to produce a regulating device that shall be useful in connection with said instrument and elsewhere and which shall be continuously adjustable, rugged, durable, free from internal contacts, and not likely to get out of order, and which shall be reasonably quiet in operation.

The single figure of the accompanying drawing is a sectional perspective view of these improvements in detail combined with a simplified and abbreviated diagram of the electrical circuits including those portrayed in said application.

The construction, action, and operation of this improved instrument are quite similar to the one portrayed in said application; therefore, this application will only concern itself with differences where they exist. Similar terminology will also be used.

Character 3 is an armature to be tested; 4, its commutator.

Section transformers are herein designated as 8 and the supply circuit as 9.

I have found it desirable to use voltages in supplying the instrument so markedly different from commercial line voltages that I prefer to interpose a feeding transformer, 10, between the source of supply, 11, and the instrument.

By connecting adjustable shunts across the indicator 12 the instrument can be made adjustable. It is immaterial whether these shunts be non-inductive or inductive resistances. I have therefore shown a carbon compression rheostat, 13, to illustrate such a shunt.

As all forms of resistance rheostats involve contacts with all the vagaries and variations that go with contacts, I prefer to use adjustable impedances or choke coils for the said shunts. The windings of such an impedance choke coil or coils are designated as 14.

I prefer to adjust the impedance of said coils by altering the length and the area of the air gap. To accomplish this, I form the coils, 14, around poles or teeth, 15, carried by

yoke, 16, which is preferably rigidly supported.

To provide for variation of the air gap, I prefer to form the face of the poles, 15, tapered or conical, and to provide an armature, 18, with a reverse tapered or conical face so that as said armature is advanced into position opposite said poles, 15, the air gap will be shortened at the same time its area is altered.

I prefer to control the position of the armature, 18, and/or the short circuiting element, 28, by a screw thread such as 22 and nut, 23, and to mount said armature in a carrier such as 19 and to support said carrier on any suitable member as shaft 20.

The shaft, 20, may be mounted in any suitable manner as in end plates or covers, 24 and 25, the latter also supporting the core 15, 16. These end plates may be supported by the case 26.

The successive coils, 14, are oppositely polarized as in any other multipolar structure.

As at times the current in said coils does not exactly match and therefore would interfere with each other, I provide shunt poles or teeth, 17, which will serve to by pass any inequality in the magnetism linked with said coils.

By placing a choke coil, 14, or coils, so that the pole faces are symmetrically spaced and all acting on a common armature their magnetic pulls balance each other and are therefore quiet in operation.

Adjustment of this instrument for armatures of different impedances is accomplished by inserting commutator, 4, between the contact fingers, 5, then adjusting the lamp shunts or rheostats, 13, or better still the choke coil lamp shunts, 14, 15, through window, 27, in case, 26, until the indicating lamps, 12, are at an appropriate voltage, as about half.

Only one of the contact fingers, 5, (Figure 1) is shown. The others are represented by arrow heads, 7.

My invention may be embodied in many different ways, the embodiment illustrated being used only as a vehicle for disclosure; therefore, I wish to have my invention construed by the appended claims:

Having now described my invention, I wish to claim:

1. In an adjustable impedance, the combination of a magnetic core having a plurality of symmetrically spaced pairs of poles, electrical windings around said poles, an armature adapted to engage the poles of said core, the engaging faces of said poles and said armature being tapered so that the movement of one relative to the other will effect a change in the length of the air gap.
2. In a regulating device, a magnetic core, a plurality of choke coils placed on poles of a magnetic core, an armature for closing the magnetic circuit through said poles, with shunt poles placed between said choke coils for shunting any magnetic inequality between said magnetic poles.
3. In a regulating device, the combination of a magnetic core having poles, a plurality of choke coils placed on poles of said magnetic core, shunt poles placed between said coils, faces of said poles being tapered, with an armature for closing the magnetic circuit, the engaging face of said armature being tapered.
4. In a regulating device, the combination of a magnetic core having tapered poles, choke windings upon said magnetic core, an armature with tapered face, means for supporting said elements including a supporting member attached to one element and a bearing attached to the other to permit of positioning one element with reference to the other.
5. In a regulating device, the combination of a magnetic core, choke windings upon said magnetic core, an annular armature the face of said armature and the poles of said core being tapered, a shaft attached to one element and a bearing attached to the other with means for positioning one element with reference to the other.
6. In a regulating device, the combination of a magnetic core, choke windings upon said magnetic core, an armature tapered to engage the poles of said core, a supporting shaft attached to one element, a bearing attached to the other, and a nut and thread so attached to said elements that the rotation of one will cause an adjustment between said armature and said core.

In testimony whereof I hereunto affix my signature this 13 day of Sept., 1929.

PENROSE E. CHAPMAN.
